DESIGN FOR A RAILWAY-HIGHWAY GRADE-CROSSING WARNING SIGNAL

Marion G. Slawson, Girard, Kans.

Application December 10, 1940, Serial No. 97,242

Term of patent 14 years

To all whom it may concern:

Be it known that I, Marion G. Slawson, a citizen of the United States, residing at Girard, in the county of Crawford and State of Kansas, have invented a new, original, and ornamental Design for a Railway-Highway Grade-Crossing Warning Signal, of which the following is a specification, reference being had to the accompanying drawing, forming part thereof,

Fig. 1 is a front elevational view of the railway-highway grade-crossing warning signal showing my new design; and

Fig. 2 is a side elevational view of the same.

I claim:

The ornamental design for a railway-highway grade-crossing warning signal, as shown.

MARION G. SLAWSON.
